UNITED STATES PATENT OFFICE

2,570,049

FUEL OIL SPACE HEATER

Robert C. Densel, Convoy, Ohio

Application July 14, 1947, Serial No. 760,824

3 Claims. (Cl. 126—94)

1

This invention relates to fuel oil space heaters. It is an object of the present invention to provide a fuel oil burning heater which is less expensive to operate than standard oil burners and which is adaptable to flue and draft conditions under which the standard burners cannot operate.

It is another object of the present invention to provide a fuel oil heater which will burn heavy furnace oils without producing soot and carbon.

It is another object of the present invention to provide a space heater wherein the mixing of the air and fuel oil is made at the bottom of the large central vessel so that intense heat will be generated at the bottom of the same whereby to provide a large body of the flame throughout substantially the entire height of the central receptacle.

Other objects of the present invention are to provide a heavy fuel oil space heater which is of simple construction, easy to be controlled, inexpensive to manufacture and efficient in operation.

For other objects and for a better understanding of the invention, reference may be had to the following detailed description taken in connection with accompanying drawing, in which

Fig. 1 is a cross-sectional view, in elevation, of my fuel oil space heater showing the central chamber and various conduits for conducting air thereto and the controls therefor.

Figs. 2 and 3 are cross-sectional views taken respectively on lines 2—2 and 3—3 of Fig. 1.

Fig. 4 is a fragmentary and enlarged cross-sectional view taken of the bottom end of the central air inlet pipe extending to the bottom of the fire vessel.

Referring now to the figures, 10 represents a furnace casing in the bottom of which is a fire pot or vessel 11. The vessel 11 is suspended from an inwardly extending flange 12 having an opening 13 of less diameter than the diameter of the vessel 11. Removed from the casing 10 is a fuel oil tank 14 having an inlet pipe 15 which extends to the exterior of an outer enclosure 16. From the bottom of the fuel tank there extends an outlet pipe 17 with a valve 18 therein adapted to deliver a controlled amount of fuel oil to the bottom of vessel or pot 11. The vessel 11 has its walls perforated as indicated at 19. Intermediate the height of the vessel 11 is a ring 21 which serves as a baffle for the flame which leaves the bottom of the vessel 11. Some air will enter the vessel through the perforations 19 above the baffle ring 21 and other air will enter the vessel through perforations 22 located below the ring 21. About the vessel 11 is an air chamber 23 into which air is delivered through a large pipe 24 having a damper valve 25 therein. When the chamber 23 is being supplied entirely through the pipe 24, the heater will be operated by natural draft, with the air entering the enclosure 16 through openings 5 in the wall thereof.

A central air delivery tube 26 extends upwardly from the bottom of the vessel 11, radially across

the top of the casing 10 and thence downwardly for connection with the top of air delivery pipe 24. The bottom end of the pipe 26 has holes 27 inclined downwardly and outwardly as shown clearly in Fig. 4 whereby to direct a flow of hot air onto the surface of the oil contained in the bottom of the vessel 11. This air descending pipe 26 is thoroughly heated by the flames leaving the pot through opening 13 of the plate 12. Flames pass upwardly about the pipe 26 and over transversely extending pipes 28 through which exterior air is circulated from the sides of the casing. Above two of these pipes 28 is a baffle 29 for causing a lateral movement of the flames and products of combustion before entering chimney pipe 31. This pipe 31 passes outwardly through the outer casing 11 and upwardly. An opening 32 is provided on the side of the casing 10 through which access can be had to the casing 10 for the purpose of cleaning the interior thereof. A cover 33 is secured to this opening.

On the exterior portion of the pipe 26 there is connected an air delivery pipe 34 through which air will be extended under pressure by means of an electrically driven air fan 35.

By having the holes 27 of the hot air tube 26 drilled at an angle, hot air will be caused to wash over the oil in the bottom of the pot causing a fastener and more thorough evaporation of the oil and to produce a vapor which will quickly and thoroughly mix with the incoming air from the perforations 19 and 22 in the side wall of the vessel 11. This will make a clean burning and highly efficient mixture. This feature alone adds considerably to the efficiency of the heater.

When the chimney draft is being used alone, the damper 25 which is balanced remains in the position as shown in Fig. 1 to permit the entrance of air through the pipe 24 to the chamber 23.

When the fan or blower 35 is started, damper 25 closes automatically since the air blast strikes the edge of the damper upon descending downwardly through the exterior portion of the pipe 26. Air pressure builds up instantly whereby to hold the damper closed until the blower 35 stops. At that time the damper will open immediately and the chimney draft will take over the operation of the burner.

In the exterior portion of the pipe 26 are respectively manually operated dampers 37 and 38 rotated respectively at opposite sides of the blower tube 34 and its connection with the exterior portion of the pipe 26. Control knobs 40 and 41 are located on the exterior casing 16 and are connected respectively with the dampers 37 and 38 to operate the same. When using the blower 35 any atmospheric condition or size of flue can be compensated for by these dampers. To increase the force of air, the dampers are adjusted to closed positions. When the dampers are opened, outside air is utilized. Each damper is adjusted until a clean and lively flame is had without

any roaring noise and are left in these positions until flue or air conditions change.

Within the air delivery pipe 34 is an aluminum vane 42 which automatically operates chimney damper 43. When the blower cuts off, the chimney damper 43 is moved to a wide open position. Accordingly the blower 35 serves not only to supply air to the burner vessel 11, but also provides power to operate damper 43. The vane 42 is connected to the damper 43 by linkage 44.

The aluminum vane 42 completely obstructs the path of the air from the blower 35. As the air blast strikes the vane, the vane is lifted to the top of the pipe 34 and remains in that position until the blower stops. In rising, the vane 42 lifts the linkage 44 to partially close damper 43 so that only a small opening between it and the pipe 31 remains. This is a principal feature of the invention. The heater is accordingly automatically made adapted to all flue and air conditions and the high heat loss up the flue is not present. Since the blower furnishes all the air needed to feed the fire, a strong chimney draft is unnecessary. Without the automatic damper 43 which is closed when the blower is used, a high heat loss up the chimney would result. An ordinary draft regulator may be provided in the chimney 31 above the damper 43 as indicated at 45.

While various changes may be made in the detail construction, it shall be understood that such changes shall be within the spirit and scope of the present invention as defined by the appended claims.

I claim:

1. In an oil burning furnace, the combination which comprises a substantially enclosed casing having a stack connection at the upper end, spaced transversely disposed hot air tubes extended through the upper part of the casing, and a sleeve extended from an opening in the lower part of the casing providing an air intake, a fire pot having a perforated wall spaced from the casing and having a centrally disposed opening in the upper end, means for supplying fuel to the fire pot, a blower positioned at one side of the casing, means connected to the discharge of the blower forming an air chamber, conduit means connecting the air chamber with the lower sleeve providing the air inlet tube, and an air tube extended from said air chamber upward on the outside of the casing and downward through the center of the casing and into the fire pot through the opening in the upper end thereof, said hot air tube having openings therein spaced from the lower end thereof for discharge of air over the surfaces of fuel in the fire pot for facilitating vaporization of the fuel.

2. In an oil burning furnace, the combination which comprises a substantially enclosed casing having a stack connection at the upper end, spaced transversely disposed hot air tubes extended through the upper part of the casing and a sleeve extended from an opening in the lower part of the casing providing an air intake, a fire pot having a perforated wall spaced from the casing and having a horizontally disposed baffle therein intermediate of the height thereof and with the baffle provided with a centrally positioned opening, a horizontally disposed plate extending from the casing over the upper end of the fire pot and having a centrally disposed opening therein, means for supplying fuel oil to the fire pot, a blower positioned at one side of the casing, means connected to the discharge of the

blower forming an air chamber, conduit means connecting the air chamber with the lower sleeve providing the air inlet tube, an inverted U-shaped tube extended from said air chamber upward on the outside of the casing and downward through the center thereof with the inner end positioned in the fire pot and extended through the centrally disposed opening of the horizontally positioned plate, the inner end of said tube having openings therein spaced from the lower end and inclined downwardly for discharging air over the surface of the oil in the pot for facilitating volatilization of the oil.

3. In an oil burning furnace, the combination which comprises a substantially enclosed casing having a stack connection at the upper end, spaced transversely disposed hot air tubes extended through the upper part of the casing, and a sleeve extended from an opening in the lower end providing an air inlet connection to the lower end, a damper in the said stack connection, a fire pot having a perforated wall spaced from the casing and having a horizontally disposed baffle therein intermediate of the height thereof and with the baffle provided with a centrally positioned opening, a horizontally disposed plate extending from the casing over the upper end of the fire pot and having a centrally disposed opening therein, means for supplying fuel oil to the fire pot, a blower positioned at one side of the casing, means connected to the discharge of the blower for forming an air chamber, a baffle pivotally mounted on the blower and positioned in the said air chamber, means connecting the baffle to the damper of the stack connection whereby air pressure from the blower actuates the damper to the substantially closed position, conduit means connecting the blower discharge chamber with the lower air inlet connection, a valve in the said conduit means, an inverted U-shaped tube extended from said air chamber upward on the outside of the casing and downward through the center thereof with the inner end positioned in the fire pot and extended through the centrally disposed opening of the horizontally positioned plate, the inner end of said tube having openings therein spaced from the lower end and inclined downwardly for discharging air over the surface of the oil in the pot for facilitating volatilization of the oil.
